UNITED STATES PATENT OFFICE.

LODRICK WILLIAMS AND GUSTAF JOHNSON, OF DOERUN, MISSOURI.

COUPLING.

SPECIFICATION forming part of Letters Patent No. 783,006, dated February 21, 1905.

Application filed May 11, 1904. Serial No. 207,465.

To all whom it may concern:

Be it known that we, LODRICK WILLIAMS and GUSTAF JOHNSON, citizens of the United States, residing at Doerun, in the county of St. Francois and State of Missouri, have invented a new and useful Coupling, of which the following is a specification.

This invention relates more particularly to that class of couplings employed in connecting diamond drills to feed-screws; but those skilled in the art will readily perceive that it may be employed for other analogous purposes.

One of the objects of the invention is to provide a structure which is very simple and compact and at the same time constitutes a strong and rigid coupling or chuck which will not readily break or open to release the drill secured thereby.

Another object is to provide simple devices which will hold the drill against movement in the chuck, said devices being detachable, so that if worn or injured they may be readily removed and replaced by new ones, being, furthermore, very simple, and consequently inexpensive, in construction.

The preferred embodiment of the invention is illustrated in the accompanying drawings; but it will be apparent that the structure illustrated may be changed and modified without departing from the spirit of the invention.

In said drawings, Figure 1 is a perspective view of the coupling. Fig. 2 is a longitudinal sectional view through the same. Fig. 3 is a transverse sectional view taken on the line xx of Fig. 2. Fig. 4 is a detail perspective view of one of the jaws. Figs. 5 and 6 are detail perspective views of the dies employed.

Similar reference-numerals indicate corresponding parts in all the figures of the drawings.

In the embodiment of the invention as shown a body 10 is employed, having a cylindrical bore 11 therethrough and being provided in its opposite walls with sockets 12, opening into the bore. The upper end of the body is counterbored to provide a seat 13 for the lower end of the feed-screw shank, (designated 14.) Hinged to one side of the body by means of

pivot-pins 15 are jaws 16, which are arranged to swing into and out of the sockets 12, these jaws having angularly-disposed seats 17 arranged in their inner faces. Dies 18 are detachably fitted in the seats and are in the form of blocks having their opposing inner faces concave, as shown, and carrying sets of teeth 19, which project into the bore 11. The teeth of one die are arranged longitudinally of the bore 11, and those of the other die are located transversely of said bore, and consequently longitudinally of the jaw carrying the die. Extending from the seats 17 through the walls of the jaws are openings 20, adapted to receive a punch by means of which the dies may be unseated, as will be readily understood. The free ends of the jaws and the corresponding side of the body are provided with projecting lugs 21, having slots 22, which are disposed in alinement when the jaws are seated in the sockets. To the free end of one of the jaws is pivoted, by means of a pin 23, a locking-bolt 24, arranged to swing into the alined slots, said bolt being held in this position by means of a nut 25. As a result the jaws will be locked in their closed positions and the locking means will engage the body.

It will be apparent that when a drill-stem, as 26, is fitted in the bore 11 and the jaws swung to closed positions and locked the teeth 19 of the dies will engage said shank and hold it both against longitudinal and rotary movement in the body. This holding action is due to the arrangement of the sets of teeth at right angles to each other, as will be apparent. At the same time the dies cannot become displaced, as the stem will hold them in their seats. The drill can be easily removed by unlocking the jaws and swinging them outwardly, and when the teeth of the dies become worn said dies may be readily detached by inserting a punch into the openings 20 and driving them from their seats.

It will be seen that the structure is made up of a few parts which may be readily assembled, so that the device can be manufactured at slight expense. Because of the arrangement of the jaws fitting in the sockets the weight of the drill transmitted to the jaws

will be sustained by the body, thus relieving the pivots and locking means for the jaws of the strain thereof.

From the foregoing it is thought that the 5 construction, operation, and many advantages of the herein-described invention will be apparent to those skilled in the art without further description, and it will be understood that various changes in the size, shape, 10 portion, and minor details of construction may be resorted to without departing from the spirit or sacrificing any of the advantages of the invention.

Having thus described our invention, what 15 we claim as new, and desire to secure by Letters Patent, is—

1. In a coupling of the class described, a body having a longitudinally-disposed bore and a socket communicating with the bore and 20 having a bottom, a jaw pivoted at one end to the bottom and swinging into and out of the socket, the pivot-axis of said jaw extending longitudinally of the body, and means engaging the free end of the jaw to secure said jaw 25 in the socket.

2. In a coupling of the class described, a body having a bore and a socket communicating with the bore, and a jaw pivoted to the body and fitted in the socket, the pivot-axis 30 of said jaw extending substantially longitudinally of the bore.

3. In a coupling, the combination with co-acting pivotally-associated jaws having seats in their opposing faces, of dies detachably 35 fitted in the seats and having teeth on their opposing inner faces said dies being stationary with respect to the jaws, the teeth upon one of the dies being disposed longitudinally of the jaw and those on the other die being 40 arranged transversely of the jaw.

4. In a coupling of the class described, a body having a bore and oppositely-disposed sockets communicating with the bore, oppositely-swinging jaws pivoted to the body and 45 swinging into and out of the sockets transversely of said bore, and means for securing the jaws in the sockets.

5. In a coupling of the class described, a body having a longitudinally-disposed bore, 50 and oppositely-arranged sockets communicating with the bore, jaws fitted in the sockets, each pivoted at one end to the body, said jaws

swinging transversely of the bore, and means for securing the free ends of the jaws.

6. In a coupling of the class described, a 55 body having a longitudinally-disposed bore, a plurality of jaws pivotally mounted on the body, means for securing the jaws against their pivotal movement, said jaws having seats in their inner faces, and toothed dies detachably fitted in the seat, said dies being stationary with respect to the jaws holding the same.

7. In a coupling of the class described, the combination with a body having a longitudinally-disposed bore and oppositely-arranged 60 transversely-disposed sockets communicating with the bore, of jaws pivoted to the body and swinging into and out of the sockets transversely of the bore, and a locking-bolt pivoted to one jaw and detachably engaging the other to hold the jaws in the sockets, said bolt extending transversely of the body.

8. In a coupling of the class described, the combination with a body having a bore there-through and sockets extending through its 75 opposite walls to the bore, of jaws pivoted to the body and fitting in the sockets thereof, and a locking-bolt pivotally connected to one jaw and detachably engaging the other.

9. In a coupling of the class described, the combination with a body having a bore there-through and sockets extending through its 80 opposite walls to the bore, of jaws pivoted to one side of the body and fitting in the sockets, and a locking-bolt pivotally connected to the 85 free end of one jaw, the other jaw and the body having alined slots arranged to receive the bolt to hold said jaws in the sockets.

10. In a coupling of the class described, the combination with a body having a bore there-through and a socket extending to the bore, of a jaw hinged to the body and fitting in the 90 socket, said jaw having in its inner face a seat and an opening extending to the seat, a die fitted in the seat, and teeth carried by the die 95 and projecting into the bore of the body.

In testimony that we claim the foregoing as our own we have hereto affixed our signatures in the presence of two witnesses.

LODRICK WILLIAMS.
GUSTAF JOHNSON.
